UNITED STATES PATENT OFFICE.

MARSHALL B. LLOYD, OF MENOMINEE, MICHIGAN, ASSIGNOR TO AUTOMATIC WELDING COMPANY, OF MENOMINEE, MICHIGAN, A CORPORATION OF MICHIGAN.

CONTINUOUS PROCESS OF MANUFACTURING METAL TUBES.

1,027,864.

Specification of Letters Patent.

Patented May 28, 1912.

Application filed July 12, 1911. Serial No. 638,202.

To all whom it may concern:

Be it known that I, MARSHALL BURNS LLOYD, a citizen of the United States, and a resident of Menominee, Menominee county, 5 Michigan, have invented certain new and useful Improvements in the Art of Manufacturing Metal Tubes, of which the following is a specification.

My invention relates to the art of manufacturing metal tubes, and has special reference to improvements in the art of manufacturing butt welded metal tubes from strip stock. The invention also relates to and incidentally includes an improved 15 method of making seamed tubes which are not welded. And my invention is particularly directed to the manufacture of thin walled metal tubes of the kind used in the construction of light vehicles, such as bicycles; as distinguished from thick walled, 20 water, steam and gas pipes, which are produced by processes that are not applicable to the manufacture of thin walled tubing.

As compared with my hereinafter described invention, the present day processes of making butt seamed and butt welded metal tubing, are slow, laborious and wasteful; require plants and equipments which are large, and expensive to construct, to 25 operate and to maintain; and, produce tubing which is not dependably uniform and which in length only approximates the requirements of purchasers.

Among the objects of my invention are the following: 1st. To produce metal tubes 35 of superior quality; as to uniformity of composition; as to uniformity of cross section; as to uniformity of strength; and, as to straightness. 2nd. To produce metal tubes 40 without waste of material; in other words, to produce a full unit of tubing from every unit of flat strip stock. 3rd. To produce direct from flat strip metal stock, a succession of straight butt seamed or butt welded 45 tubes of the exact length and cross section specified by customers; *i. e.*, to perform steps of such nature and sequence that each portion of tubing shall be fully completed and its specified length determined before it 50 is severed from the parent stock; whereby many independent steps and frequently repeated operations in present processes are avoided and material, time, labor and space are saved. 4th. To produce such metal tubes 55 at less cost than has been possible hitherto;

in brief, to produce them with less labor, with labor of lower grade, with less power, with less heat, with a less expensive plant or equipment, in less time, in less space, and, as already stated, without waste of material. 5th. To produce, in continuing series, metal tubes of several sizes from strip stock of one size.

As more fully disclosed hereinafter, I attain these and other objects and results by 60 eliminating, and avoiding the necessity for, many steps commonly performed in the manufacture of butt seamed and welded metal tubes, and by reducing to a constant every factor or step in the handling or manipulation of the metal stock, performing the same acts, imposing the same strains, in identical periods of time, upon every part thereof. I set a substantially continuous 65 piece of flat metal stock in motion longitudinally, and while it is in motion and without interrupting such motion I perform upon it all of the acts necessary to form the flat strip into butt seamed tubing, 70 to weld the longitudinal seam thereof, to 75 make and maintain it in straight condition, to reduce it to specified cross section, and to deliver successive portions in the final 80 form of completed tubes of respectively 85 specified lengths.

My invention will be more readily understood by reference to the accompanying drawings, forming part of this specification, and in which I have illustrated the several steps comprising my process as practiced 90 in the machine which I find best suited to the purposes of my invention.

Figure 1 is side elevation of said machine or apparatus; Fig. 2 is a plan view thereof; Figs. 3, 4 and 5, together constitute an enlarged plan view of the machine; Figs. 3^a, 3^b, 3^c, 3^d, 3^e, 3^f, and 3^g, are cross-sectional views, illustrating the evolution or development of the tube, from the flat strip metal stock and its finished cross-section; Fig. 6, is an enlarged vertical, longitudinal section, showing the dies and a portion of the welding tools which I employ in my process; Fig. 6^a, is a vertical section on the line 6^a—6 of Figs. 3 and 6; Fig. 7, is an 100 enlarged vertical, longitudinal section of the tools which I employ for welding the edges of the stock after giving it tubular form, also the tools that I use in removing the weld bur and die by which I reduce the 105 110

tubing to given or specified cross section, the section being in the same plane as Fig. 6; Fig. 8, is a vertical cross section on the line 8—8 of Figs. 3 and 7; Fig. 9, is an enlarged transverse section on the line 9—9 of Fig. 4 showing the details of the mechanism by which I forcibly draw and maintain the stock in constant motion; Fig. 10 is a longitudinal, vertical section thereof on the line 10—10 of Fig. 4; Fig. 11, is an enlarged sectional view similar to Fig. 9, but taken on the line 11—11 of Fig. 4; Fig. 12 is a transverse section on the line 12—12 of Fig. 4 of the stock drawing mechanism and the means for operating the same; Fig. 13 is an enlarged vertical and enlarged longitudinal section on the line 13—13 of Fig. 5, showing details of the tools which I use for measuring and cutting off the tubing in specified lengths as fast as it is finished; Fig. 14, is an enlarged transverse vertical section, on the line 14—14 of Fig. 5; Fig. 15, is a still further enlarged sectional detail of the cut off mechanism, the section being taken on the line 15—15 of Fig. 13; Fig. 16, is a similar view on the line 16—16 of Fig. 13; Fig. 17, is an end view of the adjustable gage of the cut off mechanism, on line 17—17 of Fig. 13; Fig. 18 is a like end view of the tube supporting arm adjacent to the gage, as seen from the line 18—18 of Fig. 13; Fig. 19 is a side view of the cut off mechanism, disclosing the tube clamping parts; Fig. 20 is an enlarged plan view of the parts shown in Fig. 10.

The continuous tube mill shown in the drawings is one which I devised for the purpose of carrying out the herein described process. A complete understanding of its mechanical details may be gained by reference to my companion application Serial No. 638,203, of even date herewith. In this present application I will describe and refer to its constituent parts only to the extent requisite to a full disclosure of all of the steps, acts and operation embraced in my novel process. The process may be carried out with various other tools and implements and is not limited to the mill herein shown.

In carrying out my process I make use of either hot-rolled or cold-rolled flat strip metal stock of a width approximating three times the diameter of the tubing to be produced. I provide this stock in the form of metal strips each of sufficient length to produce a large number of tubes. In carrying on the process I weld or otherwise connect the strips end to end in continuing series and thereby in effect maintain a continuous source of supply of the flat strip stock. It will be understood that the strips are of uniform cross section *i. e.* of the same thickness and width. Having thus provided a source of supply of flat strip stock I dis-

pose or position the end portion of the stock in a straight line. This end portion I confine or restrict at several points and, simultaneously at such points of confinement or restriction, I perform the several acts or steps by which the stock is maintained in motion at a constant rate of speed and during such motion is subjected to forces which continuously and progressively convert it into finished, straight tubes of definite or specified dimensions.

As an aid in defining the scope of my process and to clearly indicate the points and spaces at and within which the several steps or acts are performed, I have applied 80 to Fig. 1, a number of lines marked A, B, C, D, E, F, G, H, I and J, and will refer to the several divisions distinguished thereby. The process begins with the above described continuous source of supply of flat 85 strip stock 1, at the point A and extends to the point J; that is, the process is continuously carried on and fully completed within the space between the lines or points A and J. I prefer to use strip stock 1, in 90 bundle or reel form, and the constantly replenished reel R is shown at the left hand end of Fig. 1. The end portion of the stock which I position and maintain in a straight line as aforesaid, and which is operated 95 upon at various points, is co-extensive with the distance between the lines A and J; but as hereinafter described, during the greater part of the time, the straight portion of the stock is of less length, and at cut off moments its length corresponds to the distance between the lines A and H, a finished tube then having been severed from the stock.

Having positioned the leading end portion of the stock in a straight line I limit 105 it to movement in a longitudinally straight path by confining or laterally restricting it at approximately the points indicated by letters A', B, B', C, C', D, E, F, F', G and H. I impart constant speed longitudinal 110 movement to the straight portion of the stock, and obviously to the whole of the stock, by grasping and pulling forward upon that portion of the stock which lies in the division F—G. By such action I exert tension upon the stock, rearwardly toward the source of supply. In other words I constantly maintain under tension that portion of the stock which lies in the division F—A and simultaneously drive the stock forward at constant speed toward the point or process boundary J. Taking advantage 115 of this tension upon the stock and of the forcible drawing movement thereof, I position various tools at the points last above mentioned and thereby work the stock into desired form and condition as it progresses from the point A to the point J. These several operations involve the initial progressive formation of the flat strip 1 into 120 125 130

tubing with its edges in abutment along a straight line parallel with the axis of the tubing; then the welding of the seam edges; then the removal of the weld bur; then the 5 reduction of the tubing to specified size; then the gradual projection and measuring of the reduced tubing; and, then the severing of successively measured pieces or 10 lengths; together with incidental and intermediate steps whereby the tension upon the stock is maintained at cross sectional constants in all stages and warping is prevented, which insures the delivery of the tubing in straight, non-distorted condition. 15 Thus at a point adjacent the reel R, I position suitable forming tools or dies 2 and 3 and by proper use thereof I cause the flat stock while traversing the space B—C to 20 gradually and in a cross sectionally equal manner form into a tube with its edges in longitudinal abutment along a straight line. I will hereafter refer to this step as the forming of the tubing.

At the point B' I manipulate or control 25 the edges of the stock in such manner as to cause the seam to progressively form upon a line that is parallel with and directly above the axis of the tubing. This step is accomplished by means of the tool 4 and will 30 be hereinafter referred to as the positioning of the seam of the tubing. As stated I confine the stock at the point C'. Before it reaches that point it assumes tubular form and to there hold the stock, I apply thereto 35 tools which prevent its lateral movement in any direction. The tools which I usually employ and here show, are grooved metallic parts or rolls 5, between which I pass the tubing. These tools are so constructed and 40 positioned that they leave the seam edges of the tubing exposed between them. The steps performed by means of these tools 5 will be hereinafter referred to as the positioning and holding of the tubing against 45 lateral movement and exposing the seam edges thereof. As will be presently explained the positioning of the seam and this exposing of the seam edges have to do with the welding thereof. At the same time, and 50 using the same tools 5 for the purpose, I not only practically encompass the tubing at the point C', but also hold and press the abutting seam edges firmly together at that point. This step will be hereinafter referred to as holding and pressing together 55 the seam edges during the application of heat. And further, preferably with the same tools 5, I continuously chill the tubing, maintain a low temperature circumferentially throughout the same, at a point 60 C', omitting the chilling effect only in the seam edges which are exposed between the tools or rolls 5. This step will be hereinafter referred to as the chilling of the tubing at the welding point, and the function 65

of this step is to retain substantially the full strength of the tubing at the welding point and thus prevent the stretching or distorting of the tubing by the heavy tension to which it is subjected. Having thus 70 prepared the tubing for welding I apply heat at the point C' to the seam edges which are exposed at that point and I so localize or confine the heat that but a small portion, longitudinally considered, is raised to the welding point. This step of my process will be hereinafter referred to as uniting or welding the seam edges of the tubing. 75 Obviously as the stock is in constant forward motion, I am able to weld the seam progressively as fast as fresh seam edges enter the zone or locality of heat. The uniting of the edges by heat may be accomplished by brazing the said edges but I do not stop with a weld of that character; instead I actually unite the edges autogenously by the simultaneous movement, holding or positioning, lateral pressure and heat application here described. The tool or appliance that I prefer to use comprises an 80 oxy-acetylene gas torch G. I hold the nozzle 6' of this torch directly above the seam edges which are exposed between the rolls 5 and play the intense flame directly upon said edges at that point. The flame is directed downwardly and rearwardly toward the approaching metal.

I carefully position the seam edges in a straight line as before explained and also secure the torch in fixed relation to the seam edges, to assure uniformity of effect from 100 the flame. As the tubing passes forward under tension, the hot flame reduces the abutted edges of the tubing to a fused state whereupon as they are held against warping or 105 distending they necessarily flow or weld together. In closely observing the action of the seam edges under the flame it will be found that as the edges approach the short, narrow and intensely hot welding flame, 110 they are partially heated by the corona of the flame, but are nevertheless held closely together. I carefully proportion the temperature of the welding flame to the quantity and speed of the metal to be welded. 115 Under the intense heat of the welding flame proper the edges open apart and upward to a degree that is sufficient to admit the flame to the actual edges and the welding is practically instantaneous at this point. On moving forward, away from the flame, the edge portions quickly contract to normal condition and quickly cool. Thus the fused metal is caused to set and the weld is completed 120 before the united seam portions leave the immediate restraint or influence of the holding or pressure effecting tools. As an incidental step I prefer to cool the hot freshly 125 united seam edge portions directly after they pass the welding zone, using water 130

which is supplied by a nozzle or pipe 7. The welding of the seam edges usually results in raising a slight bur upon the tubing and the water cooling of the tubing permits the immediate use of a tool to scrape or cut away this bur. In fact I remove the bur as fast as the welding is done by using for the purpose a knife or other tool 8, at the point D, which is but a short distance from the welding torch. This step will be hereinafter referred to as removing the weld bur.

Another of the simultaneous acts which I perform upon the stock is as follows: The initially formed tubing comprises the transversely formed or bent flat strip and its circumference is substantially equal to the original width of the stock 1. It is rare that this corresponds to the circumference and diameter required in the finished tubes. Furthermore I find that I can considerably improve the weld portion of the tubing by circumferential compression of the tubing. Therefore after removing the weld bur, I further utilize the forward movement and tension of the stock and by means of a fixed tool or tools I circumferentially compress and draw down the tubing to an exact given or specified diameter and cross-section. This is done at the point E and a tool which I find useful comprises a die 9 of less diameter than the initial tubing. The tubing is drawn through this die 9 and obviously I thereby accomplish the reduction and sizing of the tubing as rapidly as it is welded and without intermediate handling of the tubing, also without pause in or interruption of the production of tubing. By changing or regulating the size of the die, I am able to produce various sizes of tubes from a single size of flat stock. Throughout the several steps herein set forth I am careful to so position the several tools and to use and operate them in such manner as to maintain a cross sectionally uniform tension in every part of the stock which lies within the division indicated by the vertical lines A and F. This step is important for I thereby avoid unequal stretching, warping or distortion of the stock and resultant tubing; in other words, I make the tubing both initially and finally straight. Through thus maintaining the tubing in straight condition in all steps it becomes unnecessary to straighten it at a later time. As is well known the forcible straightening of a bent tube invariably weakens it. I further call attention to the fact that any slight warping that may result from the welding operation is positively corrected by the act of forcibly reducing or drawing down the tubing as hereinafter described. As explained I effect the tension upon and movement of the stock by force applied longitudinally within the intermediate division F—G. At

the moment the stock is drawn into this division, draft or pulling zone, it has been reduced to its ultimate or specified cross section. Though the stock moves constantly forward, I effect the necessary drawing force entirely within the pulling zone F—G; in brief that zone is fixed and does not move. In a primary sense the then tubular stock is grasped circumferentially and a constant degree and constant speed pull or drawing is effected by a hand over hand action. While this could be done by hand with certain kinds of strip stock, the steel stock which I generally use in the manufacture of tubes, requires the use of a strong powerfully actuated tool or mechanism which will not crush, mar or distort the tubing and yet will be adequate to the overcoming of the obstacles and resistances offered by the metal stock itself and by the other operations thereon.

For the purpose of clasping the tubing circumferentially and effecting circumferentially uniform pull or tension thereon, I employ an appliance 10 which is in nature of an endless belt positioned in the space F—G. This belt carries pairs of clamping jaws set end to end thereon. The jaws are shaped to fit the tubing and each pair when closed together thereon practically incloses the portion of the tubing embraced. As will presently appear the straight upper stretch of the belt parallels the tubing. The jaws are limited to movement transversely toward and from the tubing and are carried forward in continuous series by the rotation of the belt. The jaws which at any given instant constitute the upper or working stretch of the device are in exact alinement with the tubing. They are positively closed against the tubing and the strength of their frictional engagement therewith is such that in moving forward the jaws are prevented from slipping upon the tubing and the latter is pulled or drawn through the preceding tools or dies. I rotate the belt at constant speed and cause the several pairs of jaws to successively close upon the tubing to impart movement to the tubing and to open approximately at the end of the straight stretch of the belt. By clasping the tubing in this manner, that is substantially the whole circumference of the tubing, the pull or tension is equalized throughout the circumference of the tubing, and in consequence I am able to conduct this step of my process without distorting or warping the straight tubing which enters this pulling device. As before remarked the clasping pressure whereby I secure frictional engagement of such strength as to make the movement of the stock positive, is carefully regulated to avoid crushing the tubing. In drawing the stock forward in the manner explained, I also expel or project the tubing

130

from and beyond the drawing device. Without any other or intermediate steps, and without being in any way stopped, the tubing is thus positioned in readiness for the 5 remaining steps of the process. I support the forwardly moving stock at convenient points as at H and I to maintain it in straight condition and define its path of movement. Near the delivery end of the 10 drawing device I place a cutting off tool 11. This marks the inner end point from which I measure the tubes as they are produced and I operate the cut off device at the instant that the given or specified length of 15 tubing has been projected beyond this point. I employ a measuring tool or appliance of which one part is a gage 12. In the course of the process I shift this gage toward and from said inner end measuring point, as required to determine the exact lengths of 20 successive tubes.

As shown in the drawing, I position the gage in the projected path of the tubing. Desiring to produce a tube of a certain length, 25 I place the gage at that definite distance from the inner end or cut off point, and at the instant that the forwardly moving stock strikes the gage I set the cut off tool in operation. In practice I so relate the gaging and cutting off tools that for an instant they move forward with the tubing without changing the distance between the tools. And during this movement I sever the tubing at said inner end measuring point. At 30 that time, I also remove the gage and if the next tube is to be of different length, I readjust the gage for co-action with the newly presented end of the stock. Obviously the tube which is severed will fall down out of the way and will not interfere with the return of the cut off tool to the inner end measuring point; nor does the severed or complete tube interfere with or stop the continued forward movement of the stock. 35 As a precaution against distorting the tubing at the cut off point when the tube is severed, I prefer to momentarily circumferentially clasp or clamp the tubing close to the cut off but release the tubing at the instant 40 following the action of the cut off tool. It will now be obvious that my process is continuous; and that the operations upon and the strains imposed upon each portion of the stock, are uniform with the operations and strains upon every other portion thereof. Thus in drawing the stock I am careful to 45 maintain a constant and unvarying tension and am also careful to conduct all operations at one rate of speed. In employing the tools by which I effect the progressive movement, formation and finishing of the stock, I fix their positions with respect to one another and do not change the positions. It follows that the portion of the stock between any two operating points is constant 50

as to quantity, length and state or condition notwithstanding the fact that the stock is in constant forward movement. Under these conditions the production of tubing may be carried on indefinitely, at a constant speed, 70 and the tubing produced is not only straight and therefore of great commercial value as compared with the tubing of commerce, but is also of uniform cross section, uniform strength and uniform composition. Uniformity of composition is insured by the intrinsic uniformity of the flat strip stock and by the fact that in my process the stock is not subjected to excessive periods of heat or to stresses or strains which weaken, disrupt or alter the constitution of the stock. As 75 each tube is made by cutting or separating it directly from the parent stock, and as each tube produced is of individual predetermined or specified length and requires no further trimming or cutting, it is obvious 80 that my process is conducted wholly without waste of material. By merely altering the sizes of the finishing die and pulling jaws, I can produce various sizes of tubing from the same stock. Those who are familiar with the ordinary processes of manufacturing tubing will at once perceive that many steps 85 and operations which are inherent to the older processes are entirely eliminated and avoided in and by my herein described continuous process. In marked contrast to present day processes, I am able to conduct my entire process (except the gaging or measuring step) within a space little more 90 than ten feet in length and of less width; and it is further apparent that my process is conducted with tools and machinery of a cost which is but a fraction of the cost of the equipment for carrying out the older processes. 95

To the end that every detail of my process, as practised with the herein sown tools, may be more certainly understood, I will now more fully describe the construction 100 and operation of these tools and mechanisms. 110

In the drawings, Z represents a table or bench on which I prefer to fix the several tools and whereon most of the steps of the 115 process are conducted. The construction of the forming tools or mechanism is disclosed in Figs. 1, 2, 3, 6, 22 and 23. As indicated therein, I may form the strip into a tube by means of two sets of forming dies 2 and 120 3. The first set comprises one or more pairs of rotary dies or rolls 2, 2, which shape the strip to semi-circular form in cross section. These rolls are mounted on shafts 2^a and 2^a, held in standards 2^b and connected by equal 125 speed spur gears 2^c and 2^c. The strip from the reel enters the rolls through an adjustable guide 2^x which may serve as an initial die. On leaving the forming rolls the strip enters a stationary forming die 3, compris- 130

ing an annular die 3^a and tapered mandrel 3^b, in a standard 3^c, the mandrel being adjustable on the block 3^d. The sleeve 3^e containing the die 3^a has a flaring or tapered 5 receiving throat 3^f, which may assist in shaping the strip of metal as it passes through the same. By adjustment of the parts 3^a and 3^b, I cause the edges of the stock to tightly close together. I sometimes 10 relieve the pulling strain on the stock by driving the forming rolls 2, as by means of an independently driven adjustable friction pulley 2^d (shown in Fig. 2) on one of the roll shafts 2^a. The several stages of the 15 development of the tubing are depicted in Figs. 3^a, 3^b, 3^c and 3^d. Fig. 3^a shows the cross section of the strip as it leaves the reel; Fig. 3^b shows the cross section of the strip when in the rolls 2, 2; Fig. 3^c shows its form 20 at the moment that it is about to enter the die 3; and Fig. 3^d shows the form of the tube as it emerges from the die 3. The edges of the metal strip are indicated by the character *t*, throughout the drawings; and 25 as shown in Fig. 3^d, these edges are in substantial abutment when the tube leaves the forming die 3, and form the seam which is to be closed.

To prevent the formation of a wavy seam 30 and prepare the tubing for reception by the welding mechanism, I employ a tube-seam-positioning device 4, which limits the seam to a vertical plane which includes the axis of the tubing. The tube seam positioning 35 device 4 may be a part of the forming mechanism and is one of the tools which I use in welding the tubing. As shown in Figs. 1, 3, 6 and 6^a, the positioner is at the throat of the die 3. It is a hardened steel 40 cross bar 4^a fixed to a collar 4^b which is rotatable on the sleeve 3^e. A worm gearing 4^c is provided for rotating the collar and cross bar 4^a. The ends of the bar 4^a bear on the edges of the stock, see Fig. 3^c and by 45 turning or tilting the bar one or the other edge of the partially formed stock may be depressed, and in this manner the tendency of the strip to creep or twist laterally or circumferentially in the dies may be corrected, thereby insuring a straight seam, 50 which by means of this device and the rolls 5, I am able to position in the exact manner required for the welding of the seam edges.

The welding tools are best shown in Figs. 55 2, 3, 7 and 8. One element of the welding mechanism is the oxy-acetylene gas torch 6 of which 6^a is the burner tip or nozzle, and 5, 5, are the holding pressing and chilling rolls. The tension on the tube tends to close 60 the seam but these rolls insure the desired position and condition of the tubing with respect to the torch. The rolls rotate freely in contact with the tubing. Each roll contains a peripheral groove 5^a conformed to 65 the shape of the side of the tubing. Refer-

ring to Fig. 8 it will be seen that the rolls occupy a horizontal plane and that the tube passes between them and is nearly encompassed thereby. They rotate on vertical shafts 5^b carried by adjustable blocks 5^c 70 placed in the transverse guideway 5^d. By manipulating the adjusting screws shown in Figs. 6 and 7, the two rolls 5 may be separated or moved together as required to correctly proportion their pressure upon the 75 tubing. The tops of the rolls rise above the tubing and in effect, form a deep groove having the tube seam edges at its bottom. The nozzle of the welding torch enters this groove in position to direct the flame upon 80 the seam edges at a point between the two rolls, in other words at the point where the tube is most securely held. The rolls are of such size that they rapidly absorb and radiate the heat communicated to them and serve to chill or cool all parts of the tube not exposed between the rolls. They may be additionally cooled with water supplied from pipes 5^f and overflowing through the 85 ducts 5^e. The torch is of an approved type, 90 comprising the nozzle or tip 6^a and gas conducting pipes 6^b equipped with valved nipples for the flexible gas pipes 6^c that supply oxygen and acetylene from suitable sources, (not shown). The welding torch is supported in such manner that it may be 95 quickly adjusted to working position or moved away. 6^d are brackets carrying a normally fixed arm 6^e, pivoted to which is a torch carrying lever 6^f. Stop shoulders 6^g 100 limit the downward movement of the lever. A split carrying block 6^h contains a swivel mounting 6ⁱ for the torch proper. The part 6^h is connected to the lever 6^f by a horizontal stud. This arrangement permits vertical 105 adjustment of the torch; also rotary adjustment of the nozzle. Accurate adjustment of the nozzle is obtained by a spring resisted thumb screw 6^j connecting the torch carrying block to the sustaining lever 6^f. Metal 110 which is vaporized by the welding flame sometimes condenses upon the tip of the nozzle and tends to distort the welding flame, and to maintain a uniform flame I employ a clearing device, the same comprising a metal finger 6^k on a spring returned lever 6^l pivoted at 6^m, see Figs. 3, 7 and 8. One of the two rolls 5 has pins 6ⁿ which strike and operate the lever 6^l, thereby reciprocating the finger 6^k across 115 the end of the nozzle, to periodically clean it.

The bur removing tool 8 appears in Figs. 1, 2, 3 and 7, and is preferably a planer knife, tool or blade which is rigidly held by a block or standard that contains the reducing die. The tool is vertically adjustable on the end 8^a of the arm 8^b which overhangs the standard 9. As the tubing travels beneath the sharp edge of the planer tool the latter turns cuts or scrapes off the bur, leav- 120 125 130

ing the top of the tubing as smooth as other surfaces thereof, and making the seam practically invisible. In brief, the removal of the bur is a part of the complete operation 5 of reducing the tubing to specified cross section.

The final reducing and straightening operations are performed jointly by the drawing belt or vise 10 and the die 9^a. The die 9^a is set in a sleeve 9^b that is held by the block 9. This die 9^a is considerably smaller than the newly welded portion of the tubing, hence as the tubing is drawn therethrough it is reduced in size. These stages 10 and the reduction of the tube are depicted in Figs. 3^e, 3^f and 3^g. To reduce the friction in the die I apply grease from a cup 9^c attached to the sleeve.

As best shown in Figs. 1, 2, 4, 10, 11 and 20 12, the pulling mechanism is of simple construction. One element is a wide conveyer belt composed of two endless sprocket belts 10^a that run over pairs of sprocket wheels 10^b and 10^c, and which are connected 25 by cross rods 10^d. Preferably two such bars are provided in each pair of links. The sprockets are arranged on shafts having bearings on the bench Z. The forward shaft is driven by power gearing such as 30 that shown. The upper stretch of the conveyer is supported by a bed plate 10^e which is parallel to and below the tubing. Each pair of cross rods 10^d carries two clamping or vise jaws 10^x which do not fill the space 35 between the belts 10^a and may move toward and from one another on their rods. A spring is arranged between each two jaws to hold them open. The jaws have longitudinal grooves 10^x and when closed upon the 40 tubing inclose the same. The jaws are of such length that in the straight stretches of the conveyer they meet end to end. The guide bars 10^f are adjustably secured on the bed plate 10^e. These bars are parallel. 45 Their ends diverge, to respectively receive and liberate the pairs of jaws. They serve to close the jaws upon the tubing. Excessive friction between the parts is obviated by interposed antifriction rollers 10^g, which 50 also aid the cross bars to prevent relative tilting or pivoting of the jaws when working on the tubing. The two series of rolls 10^g run in races surrounding respective bars 10^f. I adjust the pressure bars 10^f and hold 55 them parallel by means of set screws 10^h. At every instant, there are a plurality of pairs of vise jaws in clamping engagement with the tubing, the firmness with which they clamp the tube being determined by 60 the adjustment of the pressure bars 10^f. As well shown in Fig. 4 the jaws do not engage the tubing until they have risen into the plane thereof, and they are liberated from the tubing before they begin to move, 65 downwardly around the forward end of the

conveyer. A wedge-like spreader 10ⁱ having a sharp point positively spreads the jaws before they start down. The rollers 10^k carried by cross shafts serve to hold the jaws upon the bed plate.

Referring now to Figs. 1, 2 and 5 and 13 to 20 inclusive, it will be seen that the cut off mechanism takes the tubing from the drawing mechanism 10. The cutter proper is a high speed swing-saw 11, associated with a tube clamp 11^a and a gage or measuring mechanism 12, controlled by the movement of the tubing. The cutter 11 is mounted in the upper end of a swing frame 11^b and the cutter operates in a transverse plane. The 25 cutter shaft 11^c is journaled in the upper end of the swinging frame and is longitudinally movable to permit the cutter to move with the tubing while cutting it. A wide pulley 11^d is mounted on shaft 11^c and the cutter shaft is driven by a belt 11^e running over a flanged pulley 11^f. The motions of the cutter are controlled by the tubing and the measuring gage 12. A spiral spring serves to return the cutter frame after it has 30 operated. A stationary table 11^g supports a sliding carriage 12^a, movable parallel with the tubing. The carriage after operation is retracted by a weighted cable 12^b attached to the carriage. The tube clamps 35 11^a are mounted on the carriage. Each clamp comprises a movable jaw and a fixed jaw, the former arranged for operation by the measuring device 12. The cutter works in the gap between the clamps. The upper 40 jaws are operated in unison by cam shafts 11^x connected by parallel motion arms 11^y, one of which is a bell crank, having an additional arm 11^z which carries a trigger 11^u engageable with a projection 11^h on the 45 table h. In one direction the trigger is limited by a stop shoulder 11^z on the bell crank and when the carriage begins to move forward the trigger strikes the stationary projection 11^h and operates the cam shafts and clamps to connect the carriage to the 50 tube. In returning the trigger passes freely over the projection 11^h. The clamps are released at the end of the forward movement, after the cutting operation, by the 55 engagement of a projection 11^v with an arm 11^h upstanding from the stationary table, which engagement swings the cams of the clamps in the opposite direction to open the 60 clamps.

The traveling motion of the cutter is brought about by means of a lateral arm or extension 12^c rigidly secured to the carriage 12^a, and movable with it. The free end of this arm has a slotted connection with the 65 cutter shaft 11^c and operates against a collar thereon to longitudinally shift said shaft and the cutter in unison with the carriage 12^a. The slotted connection permits the 70 transverse movement of the cutter. Beneath 75

the table is a transversely slidable bar 12^d having a depending lug 12^e which constitutes the fulcrum for a latch bar 12^f extending through the upper portion of the swinging cutter frame and having a hooked end 12^g for engaging the swinging cutter frame shown in Fig. 15. The latch bar 12^f is held in position shown in Fig. 15 by a spring 12^h. The bar 12^d slides in the guides 12^a on the table 11^h. Sliding movement is imparted by a bell crank 12ⁱ pivoted at 12^j. Its arm 12^k is connected by a slot and pin connection 12^l to the carriage 12^a for operation by its movement. The arm 12^m operates the bar 12^d through link 12ⁱ which is adjustably connected to the arm 12ⁿ at 12^m. Forward movement of the carriage 12^a causes the bar 12^d to move the swinging cutter frame toward the tubing to sever the tubing. The final movement of the bars 12^d and 12^f releases the cutter frame through the striking of an adjustable cam projection 12^o on bar 12^d, against the table 11^h, and retracts the hook 12^g from engagement with the swinging frame. The cutter frame is thereupon returned by the spring before mentioned. As previously stated, the cutter marks the inner end measuring point of the tubes and as the carriage always moves with the cutter, it may be employed to operatively join the gage 12 and the cutter. The connection comprises a rod 12ⁿ rotatably mounted but longitudinally fixed in blocks 12^p on the carriage 12^a. The rod parallels the tubing. Its outer end is supported by a movable standard 12^q, in which it may slide. The length of the rod exceeds the length of the longest tube to be made. The rod carries the gage 12 which is in the form of a cross arm, adjustable on the rod, as required to measure and determine the length of succeeding tubes. One or more supports or guides 12^a are used to sustain the tube in its travel. These supports are stationary. They serve to direct the end of the tubing against the gage. Whenever this happens, the gage will be thrust forward, and this movement being communicated to the carriage 12^a through the rod 12ⁿ, the carriage will be clamped to the tubing and the tubing will be severed by the cutter, as before explained. The inner end of the rod 12ⁿ has a rocker arm 12^r which in the final forward movement of the rod and carriage rides upon a stationary cam 12^s. This action rotates the rod 12ⁿ and removes the gage 12 from the end of the severed tube, freeing both the tube and cutter carriage, whereupon the rod 12ⁿ is retractively rotated by the weight 12^a and the rod, the carriage and the cutter are retracted by the weight acting through the cable 12^b before described.

One of the several ways of starting the process is as follows: I place the end of the strip stock in the guide 2^x and enter it be-

tween the rolls 2, 2. I then turn the rolls and thereby advance the strip and begin the forming operation. I then pass a "threading" tube rearwardly through the pulling mechanism 10, the die 9, the rolls 5, 5 and the die 3^a, first removing the mandrel 3^b. Then I conform the end of the stock to the end of the tube and weld them together. This welding may be done with a hand torch, using oxygen and acetylene. To insure the gripping action of the jaws of the pulling mechanism upon the tube, I insert a temporary filler between the jaws and the tube, the filler being of sufficient length to act with the tube until the stock sufficiently enters the pulling mechanism. This filler should be a strip of soft metal of such thickness as to compensate for the difference in the sizes of the tube and the die 3^a. It may be inserted most conveniently by temporarily backing off the set screws 10^h and opening the jaws of the pulling mechanism. After it is put in place the set screws should be again tightened to restore the jaws to proper working position. Having prepared the parts in this way, I then start the pulling mechanism into rotation and thereby pull the tube and the attached stock through the several tools. When the end of the stock emerges from the pulling mechanism 10 the "threading" tube should be cut off.

The particular acts involved in the welding step of the herein disclosed process constitute the subject matter of my divisional application Serial No. 682,704, filed March 9, 1912, and are not specifically claimed in this application.

Having thus described my invention I claim as new and desire to secure by Letters Patent.

1. Setting a substantially continuous strip of flat metal stock in motion longitudinally and while it is in motion and without interrupting such motion performing upon it all of the acts necessary to progressively form the flat strip into initial tubing having a longitudinal seam, to then progressively weld said seam, to thereafter reduce the tubing from initial cross section to a specified cross section, and to sever and deliver successive reduced portions in the final form of separate tubes of respectively specified lengths.

2. Setting a substantially continuous strip of flat metal stock in motion longitudinally and while it is in motion and without interrupting such motion performing upon it all of the acts necessary to progressively form the flat strip into initial straight tubing having a straight longitudinal seam, to then progressively weld said seam, to thereafter remove the weld bur and circumferentially reduce the tubing from initial cross section to a specified cross section, and to finally sever and deliver successive reduced por-

tions in the form of separate straight tubes of respectively specified lengths.

3. Setting a substantially continuous strip of flat metal stock in motion longitudinally and while it is in motion and without interrupting such motion performing upon it all of the acts necessary to progressively form the flat strip into initial tubing having a longitudinal seam, to reduce the tubing from initial cross section to a specified cross section, and to sever and deliver successive reduced portions in the final form of separate tubes of respective lengths.

4. Setting a substantially continuous strip of flat metal stock in motion longitudinally and while it is in motion and without interrupting such motion performing upon it all of the acts and imposing stresses necessary to form the flat strip progressively into tubing having a longitudinal seam and maintaining said stresses cross-sectionally uniform in the stock and thereby insuring straightness in the tubing, and severing and delivering successive portions in the final form of separate straight tubes of respectively specified lengths.

5. Setting a substantially continuous strip of flat metal stock in motion longitudinally and while it is in motion and without interrupting such motion performing upon it all of the acts necessary to form the flat strip progressively into tubing having a longitudinal closed seam, and to sever and deliver successive portions in the final form of separate tubes of respectively specified lengths.

6. Setting a substantially continuous strip of flat metal stock in motion longitudinally and while it is in motion and without interrupting such motion performing upon it all of the acts necessary to progressively form the flat strip into initial tubing having a longitudinal seam, to position press together, fuse and weld the seam edges as the tubing progresses, to thereafter reduce the tubing from initial cross section to a specified cross section, and to sever and deliver successive reduced portions in the final form of separate tubes of respectively specified lengths.

7. Setting a substantially continuous strip of flat metal stock in motion longitudinally and while it is in motion and without interrupting such motion performing upon it all of the acts necessary to progressively form the flat strip into initial straight tubing having a straight longitudinal seam, to maintain the seam edges in straight condition, press them together and weld them as the tubing progresses, to thereafter reduce the tubing from initial cross section to a specified cross section, and to finally sever and deliver successive reduced portions in the form of separate straight tubes of respectively specified lengths.

8. Setting a substantially continuous strip of flat metal stock in motion longitudinally and while it is in motion and without interrupting such motion performing upon it all of the acts necessary to progressively form the flat strip into straight tubing having a straight longitudinal seam, to then progressively hold the seam edges together, fuse and weld them, and to finally sever and deliver successive portions in the form of separate straight tubes of respectively specified lengths.

9. Setting a substantially continuous strip of flat metal stock in motion longitudinally and while it is in motion and without interrupting such motion performing upon it all of the acts necessary to progressively form the flat strip into initial tubing having a longitudinal seam, to then progressively press together, fuse and weld the seam edges, to thereafter reduce the tubing from initial cross section to a specified cross section, and to sever successive reduced portions as separate tubes.

10. Setting a substantially continuous strip of flat metal stock in motion longitudinally and while it is in motion and without interrupting such motion performing upon it all of the acts necessary to progressively form the flat strip into initial tubing having a longitudinal seam, to then progressively hold the seam edges together and weld them and maintain the tubing in straight condition, and reduce it from initial cross section to a specified cross section, and to sever and deliver successive reduced portions as separate straight tubes.

11. Setting a substantially continuous strip of flat metal stock in motion longitudinally by cross sectionally uniform draft upon the stock at a fixed point and while it is in motion and without interrupting such motion performing upon it all of the acts necessary to progressively form the flat strip into initial straight tubing having a straight longitudinal seam as the stock is drawn toward said point, to then progressively hold the seam edges together and weld them when thus held, to thereafter reduce the initial tubing from initial cross section to a specified cross section, and to finally deliver the same in the form of straight tubing of specified cross section.

12. Setting a substantially continuous strip of flat metal stock in motion longitudinally and while it is in motion and without interrupting such motion simultaneously performing upon it at relatively fixed points all of the acts necessary to and which progressively form the flat strip into initial tubing having a longitudinal seam, then progressively weld said seam, then remove the weld bur, thereafter circumferentially compress the tubing from initial cross section to a specified cross section, and then sever and

deliver successive reduced portions in the final form of separate tubes of respectively specified lengths.

13. Setting a substantially continuous strip of flat metal stock in motion longitudinally by action upon the stock at a fixed point and while it is in motion and without interrupting such motion simultaneously performing upon it, at relatively fixed points, all of the acts necessary to progressively form the flat strip into initial tubing with a longitudinal seam, to progressively weld said seam, to reduce the tubing from initial cross section to a specified cross section, and to sever successive reduced portions in the final form of separate tubes of respectively specified lengths.

14. Setting a substantially continuous strip of flat metal stock in motion longitudinally and while it is in motion and without interrupting such motion simultaneously performing upon it at relatively fixed points all of the acts necessary to progressively form the flat strip into initial tubing having a longitudinal seam, to position the seam, to weld, to progressively weld said seam, to remove the weld bur, to thereafter compress the tubing from initial cross section to a specified cross section, and to sever and deliver successive reduced portions in the final form of separate tubes of respectively specified lengths.

15. The herein described process that consists in holding the forward end portion of strip metal stock in a definite path and by action upon an intermediate part thereof imparting longitudinal movement to the stock in said path, by said movement and by the application of transversely directed forces forming the flat portion of the stock into longitudinally seamed tubing as the stock is drawn toward the point of aforesaid action and measuring and cutting off successive end portions or tubes as such portions of the stock move forward beyond said point of action.

16. The herein described process that consists in holding the forward end portion of strip metal stock in a definite path and by action upon an intermediate part thereof imparting longitudinal movement to the stock in said path, by said movement and by the application of transversely directed forces forming the flat portion of the stock into longitudinally seamed tubing as the stock is drawn toward the point of aforesaid action, progressively uniting the seam edges by heat as the tubing is drawn toward said point, and measuring and cutting off successive end portions or tubes as such portions of the stock move forward beyond said point of action.

17. The herein described process that consists in holding the forward end portion of strip metal stock in a definite path and by

action upon an intermediate part thereof imparting longitudinal movement to the stock in said path, by said movement and by the application of transversely directed forces forming the flat portion of the stock into longitudinally seamed tubing and progressively positioning the seam in a definite line as the stock is drawn toward the point of aforesaid action, progressively holding and fusing the seam edges together as the tubing is drawn toward said point, reducing the tubing as it further progresses toward said point, and measuring and cutting off successive end portions or tubes as such portions of the stock move forward beyond said point of action.

18. The herein described process that consists in holding the forward end portion of strip metal stock in a definite path and by action upon an intermediate part thereof imparting longitudinal movement to the stock in said path, by said movement and by the application of transversely directed forces forming the flat portion of the stock into longitudinally seamed tubing as the stock is drawn toward the point of aforesaid action, positioning the seam of the tubing in a straight line, pressing the positioned seam edges together and uniting them by heat as the tubing is drawn toward said point, removing the weld bur formed by such operation, circumferentially compressing the deburred tubing as it is thus moved toward said point, and measuring and cutting off successive end portions or tubes as such portions of the stock move forward beyond said point of action.

19. The herein described process that consists in holding the forward end portion of strip metal stock in a definite path and by action upon an intermediate part thereof imparting longitudinal movement to the stock in said path, by said movement and by the application of transversely directed forces forming the flat portion of the stock into longitudinally seamed tubing as the stock is drawn toward the point of aforesaid action, circumferentially compressing the tubing as it is thus moved toward said point, and measuring and cutting off successive end portions or tubes as such portions of the stock move forward beyond said point of action.

20. The herein described process that consists in confining or restricting the end portion of a strip of flat metal stock to movement in a definite longitudinal path, applying transverse forces which form the flat stock into tubing having a longitudinal seam as the stock is drawn longitudinally forward in said path, imparting such longitudinal movement to the stock by pulling upon the formed tubing forward of the place of application of said transverse forces, and measuring and cutting off suc-

cessive predetermined lengths of the formed tubing while it is in projected movement beyond the point at which the pulling force is exerted.

5 21. The herein described process that consists in confining or restricting the end portion of a strip of flat metal stock to movement in a definite longitudinal path, applying transverse forces which form the flat 70
10 stock into tubing having a longitudinal seam as the stock is drawn longitudinally forward in said path, imparting such longitudinal movement to the stock by applying circumferentially uniform pulling forces 75
15 to the formed tubing forward of the place of application of said transverse forces, and measuring and cutting off successive predetermined lengths of the formed tubing while it is in projected movement beyond the 80
20 point at which the pulling force is exerted.

22. The herein described process that consists in confining or restricting the end portion of a strip of flat metal stock to movement in a definite longitudinal path, applying 85
25 transverse forces which form the flat stock into tubing having a longitudinal seam as the stock is drawn longitudinally forward in said path, circumferentially reducing the tubing as fast as it is thus 90
30 formed, imparting such longitudinal movement to the stock by pulling upon the tubing forward of the place of application of said transverse forces, and measuring and cutting off successive predetermined lengths 95
35 of the formed tubing while it is in projected movement beyond the point at which the pulling force is exerted.

23. The herein described process that consists in confining or restricting the end portion of a strip of flat metal stock to movement in a definite longitudinal path, applying 100
40 transverse forces which form the flat stock into tubing having a longitudinal seam as the stock is drawn longitudinally forward in said path, circumferentially reducing the tubing as fast as it is thus 105
45 formed, imparting such longitudinal movement to the stock by applying circumferentially uniform pulling forces to the tubing forward of the place of reduction, and measuring and cutting off successive predetermined lengths of the formed tubing while it is in projected movement beyond the point at which the pulling force is exerted.

55 24. The herein described process that consists in confining or restricting the end portion of a strip of flat metal stock to movement in a definite longitudinal path, applying 110
60 transverse forces which form the flat stock into tubing having a longitudinal seam as the stock is drawn longitudinally forward in said path, welding said seam as fast as it is formed and removing the weld bur, imparting such longitudinal movement 115
65 to the stock by pulling upon the tubing for-

ward of the place of application of said transverse forces, and measuring and cutting off successive predetermined lengths of the formed tubing while it is in projected movement beyond the point at which the 70
75 pulling force is exerted.

25. The herein described process that consists in confining or restricting the end portion of a strip of flat metal stock to movement in a definite longitudinal path, applying transverse forces which form the flat stock into tubing having a longitudinal seam as the stock is drawn longitudinally forward in said path, welding said seam as fast as it is formed and removing the weld bur, imparting such longitudinal movement to the stock by applying circumferentially uniform pulling forces to the tubing forward of the place of bur removal, and measuring and cutting off successive predetermined lengths of the formed tubing while it is in projected movement beyond the point at which the pulling force is exerted.

26. The herein described process that consists in confining or restricting the end portion of a strip of flat metal stock to movement in a definite longitudinal path, applying transverse forces which form the flat stock into tubing having a longitudinal seam as the stock is drawn longitudinally forward in said path, also positioning said seam and welding the seam, and reducing the tubing at successive points in said path, imparting such longitudinal movement to the stock by pulling upon the tubing forward of the place of reduction, and measuring and cutting off successive predetermined lengths of the formed tubing while it is in projected movement beyond the point at which the pulling force is exerted.

27. The herein described process that consists in confining or restricting the end portion of a strip of flat metal stock to movement in a definite longitudinal path, applying transverse forces which form the flat stock into tubing having a longitudinal seam as the stock is drawn longitudinally forward in said path, also positioning said seam and welding the seam, and reducing the tubing at successive points in said path, imparting such longitudinal movement to the stock by applying circumferentially uniform pulling forces to the tubing forward of the place of reduction, and measuring and cutting off successive predetermined lengths of the formed tubing while it is in projected movement beyond the point at which the pulling force is exerted.

28. The herein described process which consists in connecting together strips of flat metal stock end to end in continuing series, continuously holding the forward end of the stock in a longitudinal path and maintaining the stock in motion longitudinally,

- and while the stock is in motion performing upon it acts which progressively form the flat strip into initial tubing having a longitudinal seam, weld said seam, reduce the tubing to a specified cross section and sever successive reduced portions in predetermined lengths, whereby a continuing series of tubes of the same cross section and of definite lengths is produced.
29. The herein described process which consists in connecting together strips of flat metal stock end to end in continuing series, continuously holding the forward end of the stock in a longitudinal path and maintaining the stock in motion longitudinally, and while the stock is in motion maintaining it under cross sectionally uniform tension and forming it into initial tubing having a longitudinal seam, reducing the same to a specified cross section and severing successive reduced portions in predetermined lengths; whereby a continuing series of tubes of the same cross section and of definite lengths is produced.
30. Setting a substantially continuous strip of flat metal stock in tension and in motion longitudinally and while it is in motion and without interrupting such motion simultaneously performing upon it, at relatively fixed points, a succession of acts which progressively form the flat strip into butt seamed tubing, and which progressively weld the longitudinal seam thereof, which reduce the tubing to a specified cross section, and which finally determine the lengths of and sever successive portions in respectively specified lengths, by said acts making and maintaining the tubing in straight condition.
31. Setting a substantially continuous strip of flat metal stock in tension and in motion longitudinally and while it is in motion and without altering or interrupting such tension and motion progressively forming the flat strip into butt seamed tubing and positioning its seam in a straight line, progressively welding its seam edges, reducing it to a specified cross section, and severing successive end portions in respectively specified lengths, by said acts making and maintaining the tubing in straight condition.
32. The herein described process that consists in connecting together strips of flat metal stock end to end in continuing series, continuously holding the forward end portion of the stock in a straight path, and by longitudinally and transversely directed forces imparting longitudinal movement to the stock in said path and forming the stock into tubing having a longitudinal seam and measuring and cutting off successive end portions or tubes as fast as the tubing is thus produced.
33. The herein described process that consists in connecting together strips of flat metal stock end to end in continuing series, continuously holding the forward end portion of the stock in a straight path and by longitudinally and transversely directed forces imparting longitudinal movement to the stock in said path and forming the stock into tubing having a longitudinal seam and positively positioning the seam for welding, then welding said seam and measuring and cutting off successive end portions or tubes as fast as the welded seam tubing is thus produced.
34. Those steps of the herein described process, that consist in applying cross sectionally uniform longitudinal pulling and transverse compressing forces to a tube to reduce its cross section and cutting the tubing into pieces of successively predetermined lengths during such longitudinal movement of the tubing, as fast as it is reduced.
35. The herein described process that consists in positioning the end portion of a strip of flat metal stock for movement in a definite longitudinal path, applying transverse forces which form the flat stock into tubing with a longitudinal seam parallel with its axis as the stock is drawn longitudinally forward in said path, imparting such longitudinal movement by pulling upon the formed tubing forward of the place of application of said transverse forces, and measuring and cutting off successive predetermined lengths of the formed tubing while it is in projected movement beyond the point at which the pulling force is exerted.
36. The herein described process that consists in positioning the end portion of a strip of flat metal stock for movement in a definite longitudinal path, applying transverse forces which form the flat stock into tubing with a longitudinal seam as the stock is drawn longitudinally forward in said path, imparting such longitudinal movement by pulling upon the formed tubing forward of the place of application of said transverse forces, measuring successive predetermined lengths of the tubing as it is projected beyond the point of application of pulling force, and in each instance and on both sides of the inner end measuring point rigidly holding the tubing against lateral movement without interrupting its forward movement and severing the tubing at that point.
- In testimony whereof, I have hereunto set my hand, this 29th day of June, 1911, in the presence of two subscribing witnesses.
